UNITED STATES PATENT OFFICE.

CHESTER COMSTOCK, OF NEW CANAAN, CONNECTICUT.

IMPROVEMENT IN STEAM-HEATER RADIATORS.

Specification forming part of Letters Patent No. 159,155, dated January 26, 1875; application filed December 10, 1874.

To all whom it may concern:

Be it known that I, CHESTER COMSTOCK, of New Canaan, in the county of Fairfield and State of Connecticut, have invented a new and Improved Corrugated Heat-Radiator, of which the following is a specification:

Figure 1 is a vertical longitudinal section of my improved corrugated heat-radiator; Fig. 2, a vertical transverse section of the same; Fig. 3, a horizontal section thereof; and Fig. 4, a horizontal section, on an enlarged scale, of one end of the same.

Similar letters of reference indicate corresponding parts in all the figures.

This invention relates to a new radiator, to be used for hot-water or steam heating apparatus; and consists in making the radiator with sides of corrugated sheet metal, and in a peculiar way of securing this corrugated metal in the top and bottom plates of the radiator, all as hereinafter more fully described.

The letter A in the drawing represents the bottom plate or base-plate of the radiator, made of cast-iron or other suitable material, B is the body of the radiator, and C the top or head plate thereof, which is also made of cast-iron or other suitable material. The body of the radiator is formed of corrugated sheet metal, as is clearly represented in Fig. 3. The inner faces of the plates A and C are provided with sinuous grooves to receive the edges of the corrugated body B of sheet metal. The grooves in the plates A and C are wider than the metal of the body B is thick, and are also, by preference, made flaring, as clearly indicated in Fig. 2, so that the metal may be slightly bent outward therein, and so, also, that a packing-plate, a, of rubber or other substance, may be placed in each groove outside of B, and held in place by means of a metal plate, b, which is screwed down upon the rubber or other packing, all as indicated in Figs. 2 and 3. In this manner a steam-tight joint is produced in a simple manner. The metal b has also an undulating form, as clearly indicated in Fig. 3, so that it may properly conform to the outline of the corrugated body B. In order to keep the opposite sides of the body B of this corrugated radiator from springing apart or coming too close together, I interpose short tubes d between

them, and pass bolts e through these tubes, and through the body, such bolts drawing the opposite sides of the radiator together, while the tubes hold them the requisite distance apart. The tubes and bolts together serve thus to properly brace the whole body of the radiator in two directions. Vertically, the radiator is braced by means of bolts or rods f, which connect the plates A and C, as clearly shown in Fig. 1.

In constructing a radiator of the kind described it will usually be found impracticable to make its body B of one single length of sheet metal. As a general thing, it will be more convenient to make it of two pieces of sheet metal, which meet at the ends of the radiator, as in Fig. 3; and in order to properly join these pieces of sheet metal I may either lap the same together and solder the joints, or I may use a joint of the kind more fully illustrated in Fig. 4—that is to say, I place in the radiator, near to the end of the same, a V-shaped vertical rod, g, with its hollow part toward the sheet-metal body B, and bend the ends of the two sheets into the hollow part of the rod g. I then place a packing, h, of rubber or other material, into the hollow of the V, but outside of the plate B; and finally apply a T-shaped plate, i, against such packing, crowding the same against the outside of the plates B, the central wedge-shaped part, i, entering into the hollow of g, and compressing the packing, in the manner clearly indicated in Fig. 4. Small bolts j serve to connect the V-rod g with the outer plate i, and to hold the parts in proper connection.

As I am aware that corrugated sheet metal has been previously used on steam-generators and other articles, but that before my invention steam-radiators having a corrugated body, and having the top and bottom plates continuously grooved for the reception of such corrugated body, have not been known,

I claim as my invention—

1. A steam heating-radiator composed of the bottom plate, A, corrugated sheet-metal body B, and top plate, C, the bottom and top plate having each a continuous sinuous groove for the reception of the corrugated body B, and all connected and combined substantially as herein shown and described.

2. The sinuous continuous packing *a* and the sinuous continuous fastening-plate *b*, combined with the grooved end plate, *A*, and the corrugated sheet-metal body *B*, of the heat-radiator, substantially as specified.

3. The combination of the V-shaped bar *g*, packing *h*, and outer wedge-plate, *i*, with the

corrugated sheet-metal body *B* of the heat-radiator, substantially as and for the purpose described.

CHESTER COMSTOCK.
